DESIGN FOR A COMBINED CUTLERY GRINDER FAN, GUIDE, AND WHETTING DISK

Alfred M. Jacobson, Houston, Tex.

Application August 11, 1944, Serial No. 114,844

Term of patent 14 years

(Cl. D37—1)

To all whom it may concern:

Be it known that, Alfred M. Jacobson, a citizen of the United States, residing in the city of Houston, and State of Texas, have invented a new, original, and ornamental Design for a Combined Cutlery Grinder Fan, Guide, and Whetting Disk, of which the following is a specification, reference being had to the accompanying drawing, forming a part thereof.

Figure 1 is a perspective view of a combined cutlery grinder fan, guide, and whetting disk showing my new design;

Figure 2 is a side elevational view showing the reverse side thereof; and

Figure 3 is a fragmentary sectional view taken as indicated on line 3—3 of Figure 2, showing one-half of the view as an end elevation.

I claim:

The ornamental design for a combined cutlery grinder fan, guide, and whetting disk, as shown.

ALFRED M. JACOBSON.
